UNITED STATES PATENT OFFICE.

ALBERT J. GIFFORD, OF WORCESTER, MASSACHUSETTS, ASSIGNOR TO CHARLES H. MORGAN,
OF WORCESTER, MASSACHUSETTS.

GAS-PRODUCER.

No. 873,039.

Specification of Letters Patent.

Patented Dec. 10, 1907.

Application filed June 27, 1906. Serial No. 323,748.

To all whom it may concern:

Be it known that I, ALBERT J. GIFFORD, a citizen of the United States, residing at Worcester, in the county of Worcester and 5 Commonwealth of Massachusetts, have invented a new and useful Improvement in Gas- Producers, of which the following is a specification accompanied by drawings, forming a part of the same, in which—

10 Figure 1 is a central vertical sectional view through the gas producer. Fig. 2 represents a top view of a gas producer embodying my invention with a portion of the top plate removed. Fig. 3 is an enlarged view 15 of the upper portion of the annular space around the combustion chamber, and Fig. 4 is an enlarged view of the lower portion of the annular space around the combustion chamber.

20 Similar reference letters and figures refer to similar parts in the different views.

My invention relates to an improved device for feeding air to the concentric twyer of a "suction" or "downdraft" gas producer 25 located at the upper end of the gas producing chamber, in which I accomplish increased ease of repairs, and it includes means for heating the water before it is mixed in the form of steam with the air on its way to the 30 twyer, and also means for checking the air supply in order to arrest the combustion in the gas producing chamber, and it consists in the construction and arrangement of parts as hereinafter described and pointed out in 35 the annexed claims.

Referring to the accompanying drawings 1 denotes a combustion or gas producing chamber, having side walls 2 and 3, and a cover consisting of a metal plate 4 provided 40 with manholes 5, having covers 6, through which manholes the coal is supplied to the combustion chamber 1. At the center of the plate 4 is an opening 7 provided with a supporting flange 8, upon which is held an annular removable cast iron block 9 provided 45 with a depending annular flange 10 upon either side of which is bolted annular sheets 11, 11 of boiler plate iron extending downwards into the chamber 1, thereby forming 50 the twyer. At the bottom of the twyer the sheets 11, 11, are joined by a ring 12 of cast iron interposed between them. I thus provide an annular chamber 13 between the

sheets 11, 11, which is supplied with a water circulation as will be hereinafter described. 55

Above the cover 4 is a top plate 14 supported on horizontal flanges 15 surrounding the manholes 5, and a horizontal flange 16 fastened to the inside of the inclosing shell 17 of the gas producer. The top plate 14 is 60 provided with a central opening 18 having a cover 19, of sufficient size to enable the twyer to be removed; the manholes 5 also extend through openings in the top plate 14, and the top plate 14, and covers 6 and 19 are 65 provided at their edges with depending flanges which are sand sealed by a layer of sand as is usual in gas producers of this class. The top plate 14 is also provided with a series of elongated curved openings *a* provided with covers *b* having depending flanges, and which are sand sealed and extend around the gas producer, thereby affording an opportunity for removing the air pipes 20, as will be hereinafter described. 70

Between the side walls 2 and 3 of the gas producing chamber an annular space 21 is inclosed which communicates with the bottom of the gas producing chamber 1 through openings 22, thereby affording a passage for 80 the gas generated in the chamber 1 to a gas outlet 23, shown by a dotted line in Fig. 1 and communicating with the annular space. The annular space 21 is closed by an annular cover 24, provided with an upturned annular flange on the inside, which incloses a depending flange on the cover 4, and with a depending annular flange on the outside. The cover 24 is provided with a series of openings 85 surrounded by upturned flanges 26 which support collars 27 having depending flanges 28 surrounding the flanges 26. The flanges 28 are sand sealed in the usual manner. The collars 27 are attached to and support pipes 20 extending downwardly through the 90 annular space 21 and telescopically inclosing at their lower ends upwardly projecting pipes 29, having their lower ends secured in a plate 30 which closes the bottom of the annular space 21 and forms the top of an 100 annular water receptacle 31, having an annular opening 31^a to the outside air and communicating with the pipes 29, and containing water at a predetermined level below the lower ends of the pipes 29, thereby allowing air to pass upwardly through the pipes 105

29 and 20 into the space 32 inclosed between the cover 4 and the top plate 14, and as this space 32 communicates to the central twyer a supply of air is furnished to the combustion chamber 1.

The water level in the water receptacle 31 is determined by an overflow pipe 33, which is provided with a bend 34 and is rotatable. When the pipe 33 is turned with the bend 34 downward, the water in the receptacle 31 is maintained at a level below the depending flange 35 on the shell 17 of the gas producer. In this position a passage for air to the pipes 29 is provided. When the bend 34 is turned 15 upward in the position shown by dotted lines 34^a the water level in the receptacle 31 is raised above the flange 35 and the passage of air to the pipes 29 is prevented. In this way I cut off the air supply to the chamber 20 1, thereby checking the combustion in the chamber.

Water is supplied in the form of a spray against the inner side of the pipes 20 by means of nozzles 36, and the surplus water 25 not taken by the current of air in the form of steam is caught by the receptacle 31. This furnishes a supply of steam to the ascending current of air through the pipes 20. The water flowing down the inner surface 30 of the pipes 20 which does not enter the pipes 29 is held in the bottom of the annular space 21 and overflows from that space into the receptacle 31 through the pipes 29. The water is supplied to the nozzles 36 by 35 means of an annular pipe 37 which is supplied with water by a pipe 38 which is connected with the top of the annular chamber 13 of the twyer. Water is introduced into the bottom of the annular chamber 13 by a 40 pipe 39 which is connected with a source of water supply, not shown. The annular chamber 13 is therefore kept full of water which as it becomes heated passes to the nozzles 36. In this way I accomplish the 45 heating of the water supplied to the ascending current of air and also provide a water circulation in the depending twyer. The overflow water from the receptacle 31 is received by the ash pit 40 in which a water 50 seal is maintained by an overflow pipe 41 having the overflow opening above the lower edge 42 of the producer.

By removing the nozzles 36 and the covers *b* of holes *a* I am enabled to lift the pipes 55 20 from the supporting flanges 26 and out of the annular space 21. I provide annular plates 43 below the side walls 2 and 3, having upturned beveled edges 44 in the space 21, which guide the pipes 20 in the annular space 60 21 to telescope on the pipes 29.

In the operation of my gas producer, coal is fed to the gas producing chamber through the openings 5. The overflow pipes 33 are turned to maintain the water level in the

receptacle 31 below the depending flange 35, 65 thereby admitting air to the pipes 20 through the pipes 29. The air passes from the pipes 20 to promote combustion in the producing chamber through the central twyer. The gas formed by the combustion of the coal 70 passes through the openings 22 into the annular space 21 to the outlet 23, warming in its passage the air passing through the pipes 20. A spray of water is supplied to the inside of the pipes 20 through the pipe 38 and 75 nozzles 36, having been previously heated by passing through the annular chamber 13 in the walls of the twyer, thereby furnishing a supply of steam to the ascending air currents in the pipes 20 and which is by 80 them conducted into the producing chamber.

I claim,

1. In a gas producer, the combination with a gas producing chamber having an annular space surrounding said chamber and connected therewith, a twyer for supplying air to the interior of said chamber, an air pipe in said annular space open at the bottom for the admission of air and open at the top to supply air to said twyer, and means at the 85 top of said annular space for removably supporting said pipe.

2. In a gas producer, the combination with a gas producing chamber having an annular space surrounding said chamber and a twyer 95 for supplying air to the interior of said chamber, of an air pipe within said annular chamber communicating with the twyer of the producer, and a pipe communicating at one end with the outside air, said pipes being 100 telescoped together.

3. In a gas producer, the combination with a gas producing chamber having an annular space surrounding said chamber, of a cover for said annular space, and a twyer for supplying air to the interior of said chamber, of a series of air pipes within said annular space 105 removably supported by said cover, and arranged to supply air to said twyer, and a second series of pipes supported by the bottom of 110 said annular space communicating with the outside air and telescoping with the first series of air pipes.

4. In a gas producer, the combination with a gas producing chamber having an annular 115 space surrounding said chamber, of a series of air pipes in said annular space communicating with the outside air, a water receptacle below the lower end of said pipes and communicating therewith, and means for 120 varying the level of water in said receptacle, whereby said pipes are water sealed and the entrance of air prevented at will.

5. In a gas producer, the combination with a gas producing chamber having an annular 125 space surrounding said chamber and a twyer for supplying air to the interior of said chamber, of a series of air pipes in said annular

space communicating with the twyer of the producer, with the lower ends of said pipes communicating with the outside air, and adjustable means for water sealing the lower 5 ends of said pipes at will and arresting the supply of air to the gas producing chamber.

6. In a gas producer, the combination with a gas producing chamber having an annular space surrounding said chamber and connected therewith, an air pipe in said annular 10 space open at the bottom for the admission of air, and means for delivering water to the top of said pipe in contact with the inner surfaces of said pipe, said means arranged to 15 provide for the heating of said water before it is delivered to said pipe.

7. In a gas producer, the combination with a gas producing chamber, having a twyer for supplying air to said gas producing chamber, 20 of an air pipe for supplying air to said twyer, and means for supplying a current of water to said air pipe, said means including a water circulation in contact with the wall of said twyer, whereby the water supplied to said air 25 pipe is heated.

8. In a gas producer, the combination with a gas producing chamber provided with an annular space surrounding said chamber and connected therewith, a twyer for supplying 30 air to the interior of said chamber, air pipes in said annular space, and a pipe for supplying water to said air pipes, said pipe emptying into and delivering from an annular

space surrounding said twyer, whereby said water supplied to said air pipes is heated. 35

9. In a gas producer, the combination with a gas producing chamber, a twyer for supplying air to said chamber, air pipes for supplying air to said twyer, means for supplying water to said air pipes, said means comprising 40 a water circulation through an annular chamber surrounding said twyer, whereby said water is heated.

10. In a gas producer, the combination with a twyer and an annular space surrounding the combustion chamber and communicating therewith, of a series of removable air pipes inclosed in said annular space, collars attached to said pipes having depending flanges, means for sealing said depending 45 flanges, the upper ends of said pipes communicating with said twyer and the lower ends of said pipes communicating with the outside air.

11. In a gas producer, the combination 55 with an annular space surrounding the combustion chamber and communicating therewith, of a series of air pipes inclosed in said annular space for feeding heated air to the combustion chamber, said pipes consisting of 60 telescopic sections.

Dated this 23rd day of June 1906.

ALBERT J. GIFFORD.
